UNITED STATES PATENT OFFICE.

THOMAS EDWARD GIBBS, OF MOOSE JAW, SASKATCHEWAN, CANADA.

HORSESHOE.

1,316,571.

Specification of Letters Patent. Patented Sept. 23, 1919.

Application filed August 17, 1917. Serial No. 186,761.

To all whom it may concern:

Be it known that I, THOMAS EDWARD GIBBS, a subject of the King of Great Britain, and a resident of the town of Moose Jaw, in the Province of Saskatchewan, Dominion of Canada, have invented certain new and useful Improvements in Horseshoes, of which the following is a specification.

This invention relates to improvements in horseshoes, and the objects of the invention are to facilitate giving to the shoe the desired amount of cushioning best adapted to suit the well working of a horse, to permit of the cushion pad being readily removed and replaced to suit the conditions of the work which the horse is performing, to prevent a horse calking itself, an accident extremely liable to happen with the ordinary form of shoe in use, to obviate slipping and generally to adapt the shoe to better perform the functions required of it.

With the above and other objects in view, the invention consists essentially of the improved construction particularly described and set forth in the following specification and drawings forming part of the same.

In the drawings:

Figure 1 is a plan view of the under side of an improved form of horseshoe.

Fig. 2 is a longitudinal section of the same.

Fig. 3 is a transverse section on the line 2-2 of Fig. 1.

Fig. 4 is a perspective view of the base plate carrying the heel calks and also the pad or cushion.

Fig. 5 is a plan view of the under side of a light draft form of shoe provided with the improved pad or cushion.

Fig. 6 is a longitudinal section of the same.

Fig. 7 is a plan view of the under side of a light draft form of shoe showing a revolving pad mounted thereon.

Fig. 8 is a longitudinal section of the same.

Like characters of reference refer to like parts in the several figures.

Referring to the drawings, and particularly to Figs. 1-4, A represents a horseshoe provided with the usual toe calk 10 and having the rear ends of the shoe connected by a transversely extending plate 11 preferably formed integral with the shoe.

This plate is provided intermediate of its length with a boss 12 having a threaded ori-

fice 13 therethrough, while the rear ends of the shoe are provided with orifices 14, the object of which will be made clear hereinafter.

Operatively mounted on the rear of the shoe A is a rubber or like pad B carried by a base plate 15, which is provided on its upper face with a cylindrical boss 16 adapted to embrace the boss 12 on the plate 11 and an orifice 17 extends through the plate 15 to permit of the screw 18 being threaded into the orifice 13, so holding the plate 15 in assembled position with the shoe A.

The plate 15 is provided on its under face with an annular flange 19 concentrically arranged around the orifice 17, and adjacent to this flange a pair of orifices 20 are provided so that the rubber forming the pad B and which is molded around the plate 15 will pass through these orifices 20, and so connect that part of the rubber located between the plates 15 and 11, with that part which is located below the plate 15 thus making the pad B homogeneous throughout. The pad B is formed with a pocket 9 which surrounds the annular flange 19.

On the ends of the plate 15 a pair of calks 21 are secured having projections 22 designed to engage with the orifices 14 in the shoe A, while the points of the calks extend just beyond the face of the pad B, so that the calks are protected and the horse is not likely to calk itself when working.

When pressure is brought to bear on the shoe, namely when the shoe is on the ground, the pad B will become compressed and the calks 21 will thus be able to engage with the surface of the road, and so perform the functions usually performed by the calks at present used on horseshoes.

Referring now to that form of the invention illustrated in Figs. 5 and 6, A¹ represents a shoe provided with renewable toe calks 23 of the usual type used on buggy or carriage horses. The rear of the shoe is provided with an integral plate 24, which is provided intermediate of its length with a boss 25 having a threaded orifice 26 therethrough, the said boss being embraced by the cylindrical boss 27 formed on the upper face of the base plate 28, which is embedded in the rubber or like material forming the pad B'.

The plate 28 is provided with a plurality of orifices 29 and is further provided on its lower face with an annular flange 30 concentrically arranged around the orifice 31 which

extends through the plate 28 and so permits of the screw 32 being threaded into the orifice 26 to thus hold the plate and rubber pad B' in assembled position on the shoe.

5 The pad B' is thus formed with a pocket 8 surrounding the annular flange 30. By providing the orifices 29, the rubber molded on the plate 28 is uniformly connected both above and below the same, so that there is 10 no liability of the rubber breaking when the shoe is in use.

In that form of the invention illustrated in Figs. 7 and 8, the shoe A² is provided with the usual toe calks 33 and is formed 15 with the transversely extending plate 34 formed integral with the rear end of the shoe.

This plate is provided intermediate of its length with the boss 35 having a threaded 20 orifice 36 therethrough, which boss is designed to be embraced by the cylindrical boss 37 carried by the plate 38. This plate is provided on its lower face with an annular flange 39 concentrically arranged 25 around the screw 40, which is threaded into the orifice 36 to hold the plate 38 and rubber pad B² in position.

The plate 38 is embedded in rubber forming the pad B², which is molded or otherwise secured therearound, and the pad B² and plate 38 are capable of revolving, the pad being provided with a concentric pocket 7 surrounding the annular flange 39. The assembling of the several parts will be 35 readily understood from the foregoing description.

When a shoe such as is illustrated in Figs. 1-4 is in use the pad B and plate 15 embedded therein are secured to the shoe by 40 means of the screw 18, and when pressure is brought to bear upon the pad B, the desired yield is given and the cushioning effect is thus transmitted to the shoe.

During this compression of the rubber 45 B forming the pad, the calks 21 engage the surface of the road thus performing the functions usually performed by calks at present in use, but eliminating any possibility of calking of the horse taking place.

50 The pocket 9 when the pad is compressed will give an excellent grip on the road owing to the fact that a partial vacuum will be formed therein and thus slipping will be almost entirely eliminated.

55 In replacing the pad it is only necessary to enter the projections 22 into the orifices 14, whereupon the cylindrical boss 16 will embrace the boss 12 of the plate 11, and on threading the screw 18 into the orifice 13 60 the pad will thus be secured in the desired assembled position with the shoe.

When that form of the invention illustrated in Figs. 5 and 6 is in use and pressure is brought to bear on the pad B', compression of the pad takes place, and the desired cushioning is transmitted to the shoe. In removing this pad B' and plate 28 embedded therein, it is only necessary to remove the screw 32, when the pad and plate may be bodily removed and replaced by a 70 new one, which will be secured in position by re-threading the screw 32 in the orifice 26. The pocket 8 in the pad B' will perform the functions above described with respect to the pad B.

75 Referring now to that form of the invention illustrated in Figs. 7 and 8, the pad B² has, like the others above described, the desired resiliency which gives to the shoe the cushioning effect when pressure is 80 brought to bear upon the said pad.

The pad B² and plate 38 may be removed by removing the screw 40, and the new pad and plate mounted on the shoe A² by threading the screw 40 in the orifice 36.

85 In this form of the invention, however, the pad B² and plate 38 can be rotated in a horizontal plane so that should there be any tendency of the pad to wear unduly on one side, this is readily rectified by rotating the 90 pad into a new position, so that a uniform wear of the same will take place.

95 As many changes could be made in the above construction and many apparently widely different embodiments of my invention, within the scope of the claims, constructed without departing from the spirit or scope thereof, it is intended that all matter contained in the accompanying specification and drawings shall be interpreted 100 as illustrative and not in a limiting sense.

What I claim as my invention is:

1. A pad for horseshoes comprising a cup-shaped member having an annular flange extending around the base thereof, a base 105 plate, resilient material molded around the base plate to form a pad, and a pocket in the under face of the said material, said flange being closely surrounded by said material, and the walls of said pocket fitting 110 snugly around said cup member, the cup being lower than the material and being secured to the base plate.

2. The device of claim 1, with diametrical extensions on the flange and calks carried by the extremities thereof.

In witness whereof I have hereunto set my hand in the presence of two witnesses.

THOMAS EDWARD GIBBS.
